ABSTRACT OF THE DISCLOSURE

Concentric tubes spaced and secured together by radial teeth extending therebetween to provide concentric passageways for gas and oil. The inner tube exceeds the outer tube in length. The outer tube has at one end a slidably mounted sleeve for engagement with a similar outer tube of an adjacent unit. The outer tube has external sealing rings adjacent to but spaced from each end. The inner tubes of adjacent units are spliced together and the splice is covered by said slidable sleeve.

This invention relates to a device which may be used to isolate any desired section of the production casing in a well when the particular section has been pierced by either natural or artificial means.

It is a particular object of this invention to provide a device as aforesaid which not only will seal off a desired section of casing, thereby sealing off the break or puncture which appears within that section of the casing, but will permit pressure of oil and/or gas in the casing below the device to be vented while the device is in use.

It is a further object of this invention to provide a device as aforesaid which, while sealing off perfectly a predetermined section of casing which has been broken or pierced, is itself retrievable and does not interfere with retrievability of the casing itself.

It is a further object of this invention to provide a device as aforesaid which may be handled by standard tube handling equipment through the use of ordinary field labor and supervisory personnel.

It is a further object of this invention to provide a device as aforesaid which operates as long as necessary to isolate a particular section of tubing but which may be withdrawn without further plugging effect on the break or perforation such as would occur in conventional cementing practice.

The above and other objects will be made clear from the following detailed description when taken in connection with the annexed drawings, in which:

FIGURE 1 is a cross-sectional three-part view in which the three parts (in practice) are in alignment consecutively from left to right of the figure;

FIGURE 2 is a view similar to FIGURE 1, but taken on the line 2—2 of FIGURE 1;

FIGURE 3 is a view taken on the line 3—3 of FIGURE 2;

FIGURE 4 is a view taken on the line 4—4 of FIGURE 2;

FIGURE 5 is a section on the line 5—5 of FIGURE 1;

FIGURE 6 is a section on the line 6—6 of FIGURE 5; and

FIGURE 7 is an enlarged detail view of FIGURE 5 in the region of the line 6—6.

Referring now to FIGURE 1, a continuous string of casing is indicated by the numeral 10, while breaks in the casing at various levels are indicated at 12. Conventionally, such breaks as 12 have been sealed off heretofore by a cementing process in which cement under pressure is driven from the interior of the casing into the breaks 12. The cementing process, however, renders the casing below

2

the break irretrievable, and frequently extends well above the break, thus rendering even more of the casing irretrievable.

The present invention contemplates means for sealing off considerable lengths of sub-surface casing between predetermined points so that the casing itself remains retrievable and the instrumentality of this invention is equally retrievable. Such a procedure has the added advantage that while it may be desirable at one stage of operation to seal off an intermediate zone which has been broken or perforated, it may become desirable later to reopen the zone and drain the strata immediately adjacent the breaks. This, the present invention permits with ease.

The present invention comprises a pair of concentric pipes, an inner pipe 14 and an outer jacket 16. As shown in FIGURES 2, 3 and 4, each length of outer jacket 16 has adjacent each end a plurality of radially spaced supporting teeth 18 and has at its upper end a pair of external rubber sealing cups 20 and a similarly oppositely directed pair 22 adjacent its lower end. This arrangement of cups 20 and 22, as shown, is used when the pressure from the strata behind the break or perforation in the casing is greater than that in the well bore. If the break or perforation in the casing is open to strata which is at a lower pressure than that existing in the well bore, the cups 20 and 22 would be reversed without other change in the unit. The cups 20 and 22, which are expendable, are formed of rubber, neoprene or the like with their interiors bonded to steel rings. These cups are attached to the jacket 16 by welding the aforesaid steel rings to the jacket. The cups shown in the drawings are the types most commonly used, however, there are other types of sealing devices which may be substituted.

The jacket 16 projects well above the rings 20 and well below the rings 22. The teeth 18 support, center and guide the interior tube 14, and are secured thereto to constitute a unit. The upper end of the outer casing 16 is grooved to receive an O-ring 28, while the lower portion is grooved to receive an O-ring 30. Each of the lengths of outer casing 16 has between its lowermost ring 22 and its lowermost O-ring 30 a slidably sleeve 32 which is for the purpose of joining one unit with a consecutive unit, that is, when one casing 16 is aligned with a lower one, a sliding sleeve 32 can be pressed over the adjacent O-rings 30 and 28 of juxtaposed units and thereby effect a fluid-tight seal.

The above-described joinder of two or more sections is best shown in FIGURES 5, 6 and 7, where consecutive lengths of the inner tube 14 are joined by a conventional joint 34 and a tube 32 overlies the O-ring 28 of one outer tube 16 and the lower O-ring 30 of the outer casing 16 above it. This arrangement provides for considerable flexibility in adjusting relationships of one joint to the next one. It will be understood that fluid oil from the bottom of the well rises through the inner pipe 14, while gas from the portion of the well below the last of the sealing members rises between the inner tube 14 and the outer casing 16 and easily passes between the teeth 18 at each end of a length.

As used in this application, a "unit" comprises one section of outer shell 16, one section of inner tube 14 projecting therethrough, both sections being secured to the teeth 18 and with the inner tube 14 exceeding in length the section of outer tube 16. The unit also includes one slidably sleeve 32. As previously noted, a separable joint 34 is made between adjacent ends of inner tubes 14 and another separable joint is made by the sleeve 32 between adjacent ends of outer tubes 16. There is thus defined an inner channel or passageway through the inner tube 14 and an outer channel or passageway between the tube 14 and the outer tube 16 and the rings 20 and 22 seal off a given portion of well casing containing a break or per-

foration. The tubes 16 and 14 may be continued below the lowermost seal ring 22 and may selectively encounter either gas level or oil level below the seal. This automatically selects the channel, whether tube 14 or outer shell 16, for conveying gas or oil to the surface. Since the seal rings 22 are expendable, there is no problem in retrieving all of the units and thereafter retrieving the casing by conventional means.

While certain specific details have been disclosed herein, it is not intended that this invention be limited to the precise details disclosed.

What is claimed is:

1. A combination sealing and venting unit for oil well use comprising: a pair of concentric, imperforate tubes; means between said tubes to hold them in spaced, coaxial alignment, said means being so formed as to provide a continuous fluid passageway between the tubes; external sealing rings secured adjacent to but spaced from each end of the outer tube, said unit being adapted to be inserted in an outer casing having a break or perforation therein whereby said sealing rings engage the inner wall of the casing on both sides of the break or perforations to seal off the zone having the break or perforation, and the axial bore passage in the inner tube being separated from the fluid passageway between the tubes, and an imperforate tubular sleeve means being axially slidable on one end of the outer of said tubes to sealably but detachably join said unit to the outer tube of a similar unit.

2. A unit as set forth in claim 1, in which said tubular

sleeve means is positioned below the adjacent sealing ring of said outer tube.

3. A unit as set forth in claim 1, in which the length of the inner tube exceeds that of the outer tube.

5. A unit as set forth in claim 3, in which the length of the inner tube exceeds the length of the outer tube at both ends of the outer tube.

10 5. A unit as set forth in claim 4, in which said tubular sleeve means is below the adjacent exterior sealing ring of said outer tube, said imperforate tubular sleeve means being shorter than either of said tubes, and means on each end of the outer of said pair of concentric tubes for sealingly engaging the walls of the bore of said tubular sleeve means.
